CLAIM

The ornamental design for a gasket, as shown and described.

DESCRIPTION

FIG. 1 is a perspective view of a first embodiment of a gasket of the present application;

FIG. 2 is a top elevation view thereof;

FIG. 3 is a side elevation view thereof;

FIG. 4 is an enlarged detail of area 4 of the perspective view of the gasket of FIG. 1;

FIG. 5 is an enlarged detail of area 5 of the top elevation view of the gasket of FIG. 2; and

FIG. 6 is a cross-sectional view taken from line 6-6 of FIG. 5.

FIG. 7 is a perspective view of a second embodiment of a gasket of the present application;

FIG. 8 is a top elevation view thereof;

FIG. 9 is a side elevation view thereof;

FIG. 10 is an enlarged detail of area 10 of the perspective view of the gasket of FIG. 7;

FIG. 11 is an enlarged detail of area 11 of the top elevation view of the gasket of FIG. 8; and,

FIG. 12 is a cross-sectional view taken from line 12-12 of FIG. 11.

The dot dash broken line indicates cutoff boundaries for enlarged detailed portion views that form no part of the claim.
